(57) **CLAIM**

The ornamental design for a wireless speaker, as shown and described.

DESCRIPTION

FIG. 1 is front top right isometric view of a wireless speaker of the invention.

FIG. 2 is a top view of the wireless speaker of FIG. 1.

FIG. 3 is a bottom view of the wireless speaker of FIG. 1.

FIG. 4 is left side view of the wireless speaker of FIG. 1.

FIG. 5 is right side view of the wireless speaker of FIG. 1.

FIG. 6 is rear view of the wireless speaker of FIG. 1; and, FIG. 7 is front view of the wireless speaker of FIG. 1.

Subject matter shown in phantom lines does not form part of the design.
